UNITED STATES PATENT OFFICE

SAMUEL E. RAHE, OF RICHMOND HILL, NEW YORK

ART OF MAKING MATCHES FROM SHEET STOCK

Application filed January 9, 1926. Serial No. 80,251.

My invention relates to improvements in the art of making matches from sheet stock, usually in the form of wood veneers, and in the organization of machinery for carrying out the process. The general shop practice of making matches from sheet stock is to make them from wood veneers, the veneers being generally cut into strips the width of which corresponds to the length of a match, and the strips are then cut lengthwise of the grain into splints. If paper sheet stock is used, the splints are not generally completely formed, but are made up in card shape as for book matches, and torn off one by one. My improvements relate more particularly to the use of wood veneers, although other sheet stock may be used if it is desired to work said stock into complete splints, and carry out the dipping and boxing of these in substantially the customary manner.

Where wood veneers are used there is a great deal of loss in time and stock, from the fact that the general practice is to cut the veneer stock into splints, pass these splints through an impregnating liquid to prepare them so that they will not drop a coal, then dry the splints, then clean them, tumble them, shake them into parallel relation, and finally insert them in the carrier of a match dipping machine. All these operations are expensive, splints are lost at each operation, and there is always more or less difficulty because of the character of the splints in inserting them regularly and without breaking in the dipper. The object of my invention is to overcome these difficulties, and make the matches in such a way as to avoid all this handling, thereby cheapening the product to an appreciable extent. In carrying out my improvements I can use machines of a known character, although I prefer to have the cutting machines made in accordance with the disclosure of my Patent No. 1,693,937, Dec. 4, 1928. The organization of the machines into a complete sys-

tem is, however, I believe novel, and the machines are organized and arranged so that the veneer stock after being cut into strips suitable for manufacture into splints and matches, is never released so as to get out of shape, or have partly manufactured stock clog or escape, until the complete splints are perfectly set in the dipping machine. To this end I cut the stock strips so that each strip when cut into splints will form a charge for a row or rows in the dipper. The stock strips are placed edge to edge so that they will be advanced lengthwise of the grain, and passed in this shape through an impregnating tank, then through a drying machine, then while still held in close parallel relation, through a printing machine, where the stock may be printed so that the printing will appear on the finished material, then through a cutting machine or slitting machine, which slits the stock into parallel splints without disturbing their arrangement, and finally inserting the finished splints while still held in parallel relation into the carrier of the dipping machine. Thus it will be seen that the stock is held securely until the matches are finished. In carrying out the invention, the impregnating and printing may be omitted if desired, and in some cases dry stock may be passed simply through the printing and slitting machines, or even the slitting machine alone, and still be within my invention. All this will be better understood from the description which follows.

Reference is to be had to the accompanying drawings forming a part of this specification, in which similar reference characters indicate corresponding parts in the view.

Figure 1 is a diagrammatic view of the machine apparatus as organized to carry the improved art into effect;

Figure 2 is an enlarged longitudinal sectional elevation of a part of the apparatus; and

Figure 3 is a cross section on the line 3—3 of Figure 2.

The first step is to prepare the stock, and a veneer machine 10 which can be of any well known type, cuts the stock into strips 11, each of the width corresponding to the length of a match, and of a length to make a charge for a row or rows of matches in the carrier or dipper. These strips are arranged 5 in parallel relation on a feed table 12, and can be fed forward in any suitable way, as for instance by a belt 13 which follows a guide 14 through the impregnating tank 15. The table is merely a guide for the feed belt 15 13 to hold it flat and the strips of stock are laid upon the belt as well as upon the table so as to be carried forward by the belt. As the stock strips emerge from the tank, they are fed forward over the guide table 17, 20 care being taken to hold them in close parallel relation. I have not shown the feeding means, because the idea of feeding the stock strips is very common and well understood by those skilled in the art.

25 The wet strips are then carried through the drying machine 18, which can be any well known form of veneer drier, though I prefer that type of drier in which platens 19 and 20 open and close with relation to the stock so as to hold it flat and permit the escape of steam. After leaving the drying machine, the stock passes in its same relative position through a printing machine 21, which can be ordinary printing rolls, and 30 parallel columns of printing are printed on the stock, the printed matter being spaced so that when the stock is finally cut up, the cuts will come between the printed characters, leaving them on the finished match. This is a desirable feature for advertising purposes.

35 After leaving the printing machine, the stock goes strip by strip through the slitting machine 22, and this machine must be of such a character as to cut each strip simultaneously into parallel splints and hold them 40 in parallel relation so that they cannot be displaced. This machine is not well known, and I know of no machine except the one referred to in my application above named, 45 which does this work.

The splints after being cut and while still in parallel relation, are then inserted by mechanism 23 in the carrier 24 of the match dipping machine. This carrier may be of 55 any usual or preferred type, and the splints may be pushed into it by any preferred means. I have illustrated a conventional carrier running through openings 25 in the floor 26 above the place where the splints are inserted. The drawing shows a conventional dipping machine in which the carrier is given a long course to provide for drying the heads of the splints, and I have shown 60 diagrammatically at 27 and 28 means for

applying paraffine and match heads to the splints.

The important feature of the mechanism is to have the machines which perform the various operations on the stock and splints, 70 arranged in sequence so that the relation of the splints and stock is not changed, that is to say, the stock must be held so as to be delivered properly to the slitting machine 22, in such a manner that it may be cut lengthwise of the grain. Obviously if it is not desired to impregnate the stock the strips may be passed through the drying machine without going through the impregnating tank, and if the stock has been dried, it may 80 even be entered at the printing or slitting machine, but law and custom usually require that the match splints be impregnated for fire preventive purposes, and for most purposes the arrangement and organization 85 which I have shown is desirable.

At the risk of repetition I wish to make impressive, first, that match splints because of their lightness, their liability to sliver, their liability to become fuzzy, and their 90 size, are exceedingly difficult things to handle, and the only way to prevent loss in stock and time in handling, is to hold the splints so that they never become disturbed from their desired position, and my invention 95 has this idea in mind and provides adequately for carrying it into effect.

I claim:—

1. The improvement in the art of making matches which consists in feeding veneer 100 strips each of a size to make a charge for a row or rows of matches in the carrier of a dipping machine in a direction lengthwise of the grain and in separate but parallel relation through an impregnating bath, then 105 in the same relation through a drying apparatus, then cutting the strips into splints and holding the splints as cut in parallel relation, and finally inserting the splints in the carrier of a dipping machine. 110

2. The improvement in the art of making matches from wood veneer stock, which consists in feeding the stock strips through an impregnating bath in separate but parallel relation, then in the same relation through 115 a drying apparatus, then through a cutting machine arranged to cut the splints and hold them in parallel relation, and finally inserting the splints in the carrier of a dipping machine. 120

3. The improvement in the art of making matches which comprises cutting wood veneers into strips each of a size to make a charge of match splints for a section of a dipping machine, carrying the strips flatwise and unpiled in parallel relation through an impregnating bath and dryer, then slitting the individual strips sequentially into splints and holding the splints in undisturbed parallel relation, and finally in- 125 130

serting the thus held splints in the carrier
of a dipping machine.

4. The improvement in the art of making
matches which comprises arranging strips of
5 wood veneer flatwise and in parallel relation
one behind the other each strip being of a
size to make a charge of match splints for
a section of a dipping machine, then slitting
10 the strips sequentially while thus held into
match splints, holding the cut splints in un-
disturbed parallel relation, and finally in-
serting the splints in a dipping machine.

In testimony whereof, I have signed my
name to this specification this 6th day of
15 January, 1926.

SAMUEL E. RAHE.
